Primary Examiner — Janice Patyk

CLAIM

The ornamental design for a food packaging container as shown and described.

DESCRIPTION

FIG. 1 is a front perspective view of a food packaging container showing my new design;

FIG. 2 is a front elevation view thereof;

FIG. 3 is a side view thereof;

FIG. 4 is a top view thereof;

FIG. 5 is a bottom view thereof; and,

FIG. 6 is a rear perspective view of a food packaging container showing my new design thereof.

The broken lines in the figures illustrate the portions of the food packaging container that form no part of the claimed design.
